UNITED STATES PATENT OFFICE.

GUSTAVUS A. MONTGOMERY, OF TITUSVILLE, PENNSYLVANIA.

CASING SLIP.

Application filed April 21, 1926. Serial No. 103,579.

This invention relates in general to gripping devices especially designed for use in handling drill pipe or the like, and the present invention is designed particularly for 5 use as a casing slip for handling the drill pipe employed in rotary drilling.

The object of the present invention is to provide a casing slip of the type wherein a plurality of slips are arranged and held in 10 groups or nests to prevent any one slip from falling down into the well and jamming the casing or interfering with the drilling, in which the slips of each group are organized and assembled in a novel and advantageous 15 manner so that the parts best adapted to take the strains bear the strains and so that the slips, while held in proper assembly, have the desirable freedom of movement.

A further object resides in the provision 20 of a novel slip construction made up of separate body and liner or facings of such a character that the slip is of minimum weight to facilitate handling, and yet presents a relatively great area of the pipe whereby the 25 allowable unit pressure on the pipe is not exceeded. In carrying out this feature, the slips have liners or facings which are of greater area than the body, the liner or facing 30 preferably being of greater length than the body.

Another object resides in the provision of a slip of the type which has a separate liner made of high grade steel and a body of a less expensive grade of steel and in which the 35 liner is positively, securely and firmly mounted on its body in such manner that it may be readily released and replaced.

Other objects and advantages reside in certain novel features of the construction, arrangement and combination of parts which 40 will be hereinafter more fully described and particularly pointed out in the appended claims, reference being had to the accompanying drawings forming a part of this 45 specification, and in which:

Figure 1 is a plan view of the casing slip embodying the present invention.

Figure 2 is a sectional view on the line 2-2 of Figure 1,

50 Figure 3 is a view in horizontal section on the line 3-3 of Figure 2,

Figure 4 is a similar view on the line 4-4 of Figure 2,

Figure 5 is a view in vertical section on the line 5-5 of Figure 1,

Figure 6 is a similar view on the line 6-6 of Figure 1,

Figure 7 is a view in section on the line 7-7 of Figure 1,

Figure 8 is a detail perspective view of 60 the body of one of the slips,

Figure 9 is a detail view in plan of the liner or facing of one of the slips,

Figure 10 is a detail perspective view of 65 the liner or facing looking at the inner face thereof, and

Figure 11 is an enlarged fragmentary sectional view showing the spring pressed locking plunger.

Referring to the drawings, it will be seen 70 that the casing slip embodying the invention proposes at least two groups of slips, one group being designated at G and the other group being designated at G'. In the present embodiment of the invention three 75 slips are shown in each group, but it is to be understood that the number of slips may be varied as may be desirable.

The corresponding slips of the two groups 80 are of identical construction. Each group has a center slip 1 and the end slips 2 and 3. The slips 1, 2 and 3 are of identical construction except as will be hereinafter pointed out. Each slip includes a body 4 and a separate liner or facing 5. The body 4 is 85 cored out to lighten it, as indicated at 6. The inner face of the body is provided with a transversely or circumferentially extending groove 7 having its upper and lower walls undercut as at 8. The liner 5 associated with the body is provided with a transversely or circumferentially extending 90 rib 9 having undercut upper and lower edges 10 which snugly engage the undercut walls 8 of the groove 7, the rib 9 being slipped sideways into the groove 7. The interengagement of the rib 9 and groove 7 locks the liner to the body against all except circumferential movement. Means is provided 95 for releasably locking the liner against circumferential movement, and comprises a locking plunger 11 freely slidable in an opening 12 provided therefor in the body.

A spring 13 is associated with the plunger 11 to force the same outwardly toward the liner. The outer end of the plunger is 100 105

tapered, as indicated at 14, and this tapered end of the plunger is receivable in a correspondingly shaped opening 15 formed in the liner 5 and extending therethrough as shown 5 in Fig. 11, so that when it is desired to separate the liner from the body the plunger may be pushed back into socket 12 with any suitable tool. When the liner 5 is properly centered on the body, its opening 15 is 10 alined with the plunger 11 and the spring 13 forces the plunger 11 into the opening 15 to lock the liner on the body.

By forming the liner and body separate, the liner may be constructed of high-grade 15 steel and the relatively heavy body may be constructed of a less expensive grade of steel. Moreover, as the liner is of uniform thickness throughout, it will temper better than if it is formed integral with the body, 20 since the body must have a taper to coact with the tapered ring or bushing with which it is employed in practice.

Another important feature of the present invention resides in the provision of a liner 25 which is longer than the body, as clearly shown in the drawings. This has the advantage of distributing the gripping force over a relatively great area on the pipe, while leaving the entire slip structure relatively light and compact so that it may be 30 readily handled, an important advantage when it is considered that these slips must be handled hundreds of times daily by manual labor. Another important advantage 35 which results from this feature resides in the fact that the allowable unit pressure of the pipe is not exceeded. It is to be understood that this allowable unit pressure on the pipe is limited, and if it is exceeded 40 the slips will bend or collapse the pipe.

Each of the central slips 1 has adjacent its inner corners vertically spaced semi-cylindrical projections 20 and 21, and in between these semi-cylindrical projections 20 and 21, 45 a semi-cylindrical depression 22 is provided as illustrated to advantage in Figures 7 and 8. The portions of the slips 2 and 3 located adjacent the central slips are provided with semi-cylindrical depressions 23 50 and 24 receiving the projections 20 and 21, and between the depressions 23 and 24, semi-cylindrical projections 25 are provided, the projections 25 fitting in the depressions 22. As shown in Figure 7, the vertical extent of 55 each projection 25 is such in relation to the vertical extent of its depression 22 that a clearance space 26 is formed. The projections 20, 21 and 25 are held in their depressions 23, 24 and 22 against lateral dis- 60 placement only by means of U-bolts designated generally at 27, each U-bolt having legs 28 and 29 and a body portion 30 connecting the legs. The body of the central slip is provided with vertical openings 31 65 adjacent the projections 20 and 21, and the

recesses 22, and these openings 31 receive the legs 29 of the U-bolts 27. The bodies of the slips 2 and 3 have openings 32 formed therein adjacent the depressions 23 and 24 and the projections 25 thereof, the openings 32 70 receiving the legs 28 of the U-bolts. Adjacent their lower ends the openings 31 and 32 are enlarged laterally to extend out through the adjacent sides of the slips, and these openings are slightly larger than the 75 body portion 30 so as to not only accommodate the body portion of the U-bolt but also to provide the requisite clearance necessary to the operative movement of the slips. Each of the openings 31 is countersunk at 80 its upper end, as indicated at 33. The openings 32 are also counter-sunk at their upper ends as indicated at 34, the counter-sinks 34 being somewhat deeper than the counter-sinks 33. Near the counter-sinks 33 and 34, 85 slots 35 and 36 are provided. In the counter-sinks 33 and 34 and in the slots 35 and 36 links 38 are received, the links having openings receiving the upper ends of the legs 90 of the U-bolts.

The links 38 are held on the legs of the U-bolts by means of castellated nuts 40 and other nuts 41, the nuts 40 being threaded on the legs 28 and the nuts 41 being threaded on the legs 29. The castellated nuts 40 are held in position by the usual cotter pin. The nuts 41 are in the form of cap nuts with their upper ends transversely slotted as at 42 to provide bifurcated portions in which eyes 43 of bail-like or handle members 44 100 are received. Pivot pins 45 are provided to pivotally connect the eyes 43 of the bails or handles 44 to the cap nuts. The links and U-bolts hold the projections 20, 21 and 25 in their recesses 23, 24 and 22, and the 105 U-bolts and links take the lateral strains, but neither the U-bolts or the links are subjected to vertical strain, since the projection 25 positively engages the projections 21 or 20 to take up such strain. As the counter-sink 34 is deeper than the counter-sink 33 it provides a clearance necessary to relieve the links 38 of vertical strains.

I claim:

1. A casing slip comprising a tapered body adapted to be mounted on the tapered inner wall of the spider for free sliding movement, and a liner fixed to and longer than the body and held against longitudinal movement relative to the body, said liner having pipe-engaging means throughout its extent to present a gripping surface of relatively great area to the pipe. 115

2. A casing slip comprising a tapered body adapted to be mounted on the inner tapered wall of a spider for free sliding movement and a separate liner at least as long as the body, interlocking means between the liner and the body including a transversely extending rib on the liner, the 120 125 130

body having a groove in which said rib is snugly fitted whereby the liner is fixed to the body against all except transverse movement, and releasable means for locking the rib and liner against transverse movement in the groove.

3. A casing slip comprising a tapered body adapted to be mounted on the inner tapered wall of a spider for free sliding movement and a separate liner at least as long as the body, interlocking means between the liner and the body including a transversely extending undercut rib on the liner, the body having a similar groove in which said rib is snugly fitted whereby the liner is fixed to the body against all except transverse movement, and releasable means for locking the rib and liner against transverse movement in the groove.

20 4. A casing slip comprising a tapered body adapted to be mounted on the inner tapered wall of a spider for free sliding movement having a circumferentially extending groove provided with undercut upper and lower edges, a separate slip at least as long as the body and having a circumferentially extending rib provided with undercut upper and lower edges simultaneously engageable with both correspondingly formed edges of the groove of the body, whereby the liner is fixedly secured to the body against all except circumferential movement and means for locking the slip against circumferential movement relative to the body.

40 5. A casing slip comprising a body having a circumferentially extending groove provided with undercut upper and lower edges, a separate slip at least as long as the body and having a circumferentially extending rib provided with undercut upper and lower edges engageable with the correspondingly formed edges of the groove of the body, and means for locking the slip against circumferential movement relative to the body, and comprising a spring pressed plunger mounted on the body, the slip having an opening into which the plunger is projected.

50 6. A casing slip comprising a body having a circumferentially extending groove provided with undercut upper and lower edges, a separate slip having a circumferentially extending rib provided with undercut upper and lower edges engageable with the correspondingly formed edges of the groove of the body, and means for locking the slip against circumferential movement relative to the body, and comprising a spring pressed plunger mounted on the body, the slip having an opening into which the plunger is projected, the opening of the slip and the engaging portion of the plunger being correspondingly tapered.

65 7. A casing slip comprising a tapered

body adapted to be mounted on the inner tapered wall of a spider for free sliding movement, a separate liner longer than the body and projecting above and below the same, and interlocking means between the liner and the body for fixedly securing the liner to the body.

8. A device of the character described, comprising a plurality of casing slips having interengaging means on their lateral edges permitting relative pivotal movement of the slips, and means separate from and independent of the interengaging means for holding the interengaging means against lateral displacement only relative to each other.

9. A device of the character described, comprising a plurality of casing slips having interengaging means on their lateral edges permitting relative pivotal movement of the slips, and means for holding the interengaging means against lateral displacement relative to each other, and consisting of U-bolts, the slips having openings receiving the legs of the U-bolts and accommodating the bodies thereof.

10. A device of the character described, comprising a plurality of casing slips having interengaging means on their lateral edges permitting relative pivotal movement of the slips, and means for holding the interengaging means against lateral displacement relative to each other, and consisting of U-bolts, the slips having openings receiving the legs of the U-bolts and accommodating the bodies thereof, links connecting the legs of each U-bolt, the slips having openings receiving the links, and nuts threaded on the upper ends of the legs to hold the links and U-bolts in position.

11. A device of the character described, comprising a plurality of casing slips having interengaging means on their lateral edges permitting relative pivotal movement of the slips, and means for holding the interengaging means against lateral displacement relative to each other and consisting of U-bolts, the slips having openings receiving the legs of the U-bolts and accommodating the bodies thereof, links connecting the legs of each U-bolt, the slips having openings receiving the links, nuts threaded on the upper ends of the legs to hold the links and U-bolts in position, and handle members connected to certain of said nuts.

12. A device of the character described, comprising a plurality of casing slips having interfitting projections and depressions along their adjacent lateral faces, the projection snugly fitting in the depressions the projections and depressions being provided with rounded vertical peripheries to provide vertical hinges only between the slips, and means for holding the projections and depressions engaged.

- 4
13. A device of the character described, comprising a plurality of casing slips having interfitting projections and depressions along their adjacent lateral faces, the projections and depressions being rounded to provide hinges between the slips, means for holding the projections and depressions engaged, and comprising U-bolts, and means for holding the U-bolts against displacement. 35
14. A device of the character described, comprising a plurality of casing slips having interfitting projections and depressions along their adjacent lateral faces, the projections and depressions being rounded to provide hinges between the slips, means for holding the projections and depressions engaged including U-bolts pivotally interfitted with the slips, links having pivotal connection with the legs of the U-bolts, the slips having openings receiving the links, means for holding the links and U-bolts in position, there being clearance between the links and certain of the slips and a clearance between certain of the projections to relieve the links and U-bolts of vertical strain. 40
15. A device of the character described, comprising a plurality of casing slips having interfitting projections and depressions along their adjacent lateral faces, the projections and depressions being rounded to provide hinges between the slips, means for holding the projections and depressions engaged and comprising U-bolts pivotally interfitted with the slips, links connecting the legs of the U-bolts and also engaging the slips, and nuts threadedly engaged with the U-bolts for preventing displacement of the links and U-bolts. 45
16. A device of the character described, comprising a plurality of casing slips having interfitting projections and depressions along their adjacent lateral faces, the projections and depressions being rounded to provide hinges between the slips, means for holding the projections and depressions engaged and comprising U-bolts pivotally interfitted with the slips, links having pivotal connection with the legs of the U-bolts, the slips having openings receiving the links, means for holding the links and U-bolts in position, there being clearance between the links and certain of the slips and a clearance between certain of the projections to relieve the links and U-bolts of vertical strain. 50
17. In a device of the character described, comprising a plurality of groups of casing slips, each group of casing slips including a central slip and a pair of end slips, the central slips having along each of its inner lateral edges spaced semi-cylindrical and laterally directed projections, there being a semi-cylindrical recess between the projections of each edge of the central slip, the end slips having corresponding recesses and projections in which the recesses and projections of the central slip are fitted, and means for holding the projections of the slips operatively engaged. 55

GUSTAVUS A. MONTGOMERY.
